UNITED STATES PATENT OFFICE.

DAVID HARPER SIBBETT, OF ANN ARBOR, MICHIGAN.

PIPE FOR SMOKING.

1,033,482.

Specification of Letters Patent. Patented July 23, 1912.

Application filed January 6, 1912. Serial No. 669,906.

To all whom it may concern:

Be it known that I, DAVID HARPER SIBBETT, a citizen of the United States, residing at Ann Arbor, State of Michigan, have invented a new and useful Improvement in and to Pipes for Smoking, of which the following is a specification.

My invention relates to an improvement in tobacco pipes, into which a partition or piece of suitable metal, wire netting, is so inserted as to divide the pipe for smoking, into two compartments into which tobacco of two or more different classes may be placed at the same time. 15 This partition is made by taking a flat piece of metal and bending, pressing or molding same into such a shape as to fit snugly any size of pipe, so as to divide the same into two compartments. This partition or piece of 20 metal may be varied in its shape. The principal shape however in which it will be manufactured will be a flat piece of metal with an L or flange bent from each end in opposite directions. This L or flange may be 25 bent either to the right or to the left or vice versa. The inventor hereinafter will use the word flange in referring to this L or flange. The flanges may be of greater or 30 less magnitude to snugly fit the pipe for smoking. In a pipe for smoking the partition may also be made so as to divide a bowl of metal which would exactly conform to the inside shape of the bowl of the pipe in which used. This partition of any shape 35 mentioned herein may be of wire or of metal solid or perforated.

In the accompanying drawings Figure 1 shows a pipe with the partition therein. Fig. 2 shows a modification in which the flange is formed in a shell which fits in the pipe. Fig. 3 shows the flanged partition.

In the drawings, 10 indicates a tobacco

pipe of any desired construction; 11 indicates a partition of a shape to fit within the pipe bowl and divide the same into compartments.

As shown in Fig. 3 this partition is formed preferably of metal, stamped, cut or otherwise shaped, and at the edges, flanges 12 are bent to extend in opposite directions. 50 In bending the flanges are generally curved to fit the inner curvature of the pipe bowl, and preferably being of flexible material may be readily pressed or shaped to fit close against the sides of the bowl. The 55 partition extends practically to the base of the bowl.

In the modification shown in Fig. 2, the partition 11 is formed within a shell 13, which fits within the pipe bowl. 60

In both constructions the partition is preferably perforated so that if necessary the fire will pass therethrough so that the tobaccos in each chamber, which may be of different kinds, flavors, mixtures or grades 65 will burn evenly. The perforations may be of any desired size or shape.

Having thus described my invention, I claim:

1. The combination with a tobacco pipe of 70 a perforated partition shaped to divide the bowl into a plurality of chambers, all open at the base, and in which tobaccos may be simultaneously smoked.

2. As an article of manufacture a perforated partition having flanges conforming to the sides of the tobacco bowl of a pipe to divide the same into chambers in which tobaccos may be simultaneously smoked. 75

DAVID HARPER SIBBETT.
